UNITED STATES PATENT OFFICE.

ARTHUR F. POOLE, OF KENILWORTH, ILLINOIS, ASSIGNOR TO REMINGTON ACCOUNTING MACHINE CORPORATION, OF NEW YORK, N. Y., A CORPORATION OF NEW YORK.

CALCULATING MACHINE.

Application filed July 6, 1921. Serial No. 482,787.

To all whom it may concern:

Be it known that I, ARTHUR F. POOLE, citizen of the United States, and resident of Kenilworth, in the county of Cook and State 5 of Illinois, have invented certain new and useful Improvements in Calculating Machines, of which the following is a specification.

My invention relates to calculating machines and especially to combined typewriting and calculating machines.

My invention has for its principal object to provide certain improvements in clearance proof mechanism for the totalizers of calculating machines. One of the objects of the invention is to provide means for proving the condition of the totalizer as to clear or not clear before writing the first number of a calculation as well as after the copying 20 of the total. Another object of the invention is to provide certain detail improvements.

To the above and other ends which will hereinafter appear, the invention consists 25 in certain features of construction and combinations and arrangements of parts, all of which will be fully set forth herein and particularly pointed out in the claims.

One embodiment of my invention is illustrated in the accompanying drawings, in which—

Figure 1 is a front to rear vertical cross sectional view of part of a Remington-Wahl combined typewriting and calculating machine, some of the mechanism being shown more or less diagrammatically, and the totalizer being shown in section just inside the right-hand frame plate thereof.

Figure 2 is a view similar to parts of Fig. 40 1 but with a number of parts omitted for the sake of clearness of illustration.

Figure 3 is a similar view but with some parts broken away and with the mechanism in locked position.

Figure 4 is a rear elevation of the totalizer with much of the mechanism removed.

Figure 5 is a vertical section about on the line 5—5 of Fig. 2 and looking toward the front of the machine.

Figure 6 is a partial plan view in section about on the line 6—6 of Fig. 5.

Figure 7 is a conventional illustration of one of the type bars and type blocks of the machine.

Figure 8 is a view of the Remington-Wahl accounting machine

is well known in the art and I have therefore shown only so much of it in the drawings as is necessary to illustrate the application of my invention thereto. One form of that machine is well shown and described 60 in the patent to Wahl, No. 1,270,471, dated June 25, 1918. Reference may also be had to the patent to Wahl, No. 1,148,733 dated August 3, 1915. It will of course be understood that my invention may be applied or 65 adapted to various styles of calculating machines and combined typewriting and calculating machines.

The Remington typewriter includes character keys 10 connected to type bars 11, Fig. 70 7, each carrying two type and the upper case type can be printed by depressing a shift key 12. The Wahl adding mechanism has a stationary frame 13 suitably attached to the typewriter frame, and a truck 14 mounted 75 on three wheels, of which the upper one 15 is shown. Said truck is connected to travel with the typewriter carriage by means of brackets 16 and screws 17. One or more totalizers 18 are mounted on the truck and 80 secured in place by hooks 20 controlled by a spring 21 and a handle 22. One of the hooks 20 has a tooth 23 that latches into a rack bar 24 on the front of the truck. Each of the numeral keys of the typewriter is connected by a link 25 with a fan 26 pivoted on a stationary rod 27 in the actuator of the calculating mechanism. Each of these fans has lost motion connection with a goose-neck cam 28, which is adapted to engage a roller 30, 90 said rollers being mounted in a series of spirally arranged arms 31 rigid on a differential rock shaft 32; but the zero key, which is the one shown in Fig. 1, is connected only with a fan 26 and does not operate a goose-neck cam nor the shaft 32. Rigidly mounted on the shaft 32 is a block 33 to which is connected a gear segment 34 so that said segment rocks with the shaft 32 but can be 95 swung laterally into and out of mesh with a main driving pinion 35 in case the machine is set for addition, or with an auxiliary driving pinion 36 in case the machine is set for subtraction. The pinion 35 is splined on a shaft 37 which carries also the master wheel 100 38 which is adapted to mesh with the carrying wheels 40 of the totalizer, one at a time. The calculating mechanism is provided with a universal bar 41 mounted on arms 42 projecting from a universal rock 110

2

shaft 43 pivoted in the stationary framework of the actuator. Each of the key operated fans 26 has a projection 44 which when the key is depressed is adapted to 5 swing the universal bar 41 toward the front of the machine. At the end of the down stroke of the key said bar falls off of the rear end of the lug 44 and returns automatically to its normal position shown in Fig. 1. On the up stroke of the key said universal bar is swung backward and upward until at the end of said up stroke it again falls off of the projection 44 and returns to its normal position.

15 The full stroke mechanism of the machine comprises a series of teeth 45 on each of the fans 26 and a long pawl 46 adapted to engage said teeth on the down stroke of the key. Said pawl 46 is pivoted at 47 and it 20 has an arm 48 which overlies the right-hand end one of the arms 42 which support the universal bar. Each of said fans also has another set of teeth 50 adapted to be engaged by a second pawl 51 on the up stroke of the 25 key. Said pawl is also pivoted in the stationary framework and it has an arm 52 lying in front of the right-hand arm 42. The construction is such that during the down stroke of the key, when the universal 30 bar is swung forward, the arm 42 swings the arm 52 forward and holds the pawl 51 out of engagement with the teeth 50, but during this stroke the pawl 46 engages the teeth 45. When at the beginning of the up stroke the 35 universal bar is swung backward it acts on the arm 48 and lifts the pawl 46 out of the teeth 45, thus permitting the up stroke of the key to continue, but during said up stroke the pawl 51 engages the teeth 50.

40 The master dog 53 having thereon the locking tooth 54, is mounted on a rock shaft 55 and it has a depending arm on which is a roller 56 that runs in a cam groove in an arm 57 on a rock shaft 58 in the stationary 45 actuator. The cam arm or plate 57 has a pin 60 that engages in an elongated slot 61 in the end of a link 62, the other end of which is pivoted to an arm 63 projecting from the universal rock shaft 43. The 50 construction is such that when said universal rock shaft is operated on the down stroke of a key the link 62 is pushed upward rocking the plate 57 and swinging the master dog 53 toward the front of the machine and the 55 locking tooth 54 upward as shown in Fig. 3. Said locking tooth then engages a rack 64, mounted on the lower part of the truck 14, so that during the time when the universal bar is swung toward the front and the 60 master dog 53 is swung forward the truck is positively locked to the stationary actuator and the carriage cannot travel. The machine also contains a single key mechanism (not shown) so that when any one of the 65 numeral keys is depressed no other can be de-

pressed. The construction of the parts is also such that if the dog 53 be rocked to its position shown in Fig. 3 and held there, then the universal bar 41 cannot return to its normal position and the full stroke pawl 46 will therefore continue in engagement with the teeth 45 and prevent the depressed key from rising. When the master dog is held in its operated position therefore the carriage is locked against travel, the depressed key is prevented from rising, and all other numeral keys are prevented from being depressed, and in short the machine is locked up. I utilize this fact in connection with my clearance proof mechanism. 80

The register wheels of the Wahl totalizer include the carrying wheels 40, which are mounted on a shaft or rod 65, and said wheels mesh with idle pinions 66 mounted on a transverse shaft 67, and said pinions mesh 85 with the pinions 68 of the number wheels 70. The carrying or transferring is effected by means of certain Geneva wheels 71 which are mounted on levers 72 which are pivoted on two rods 73 and 74 and which project 90 downward, being notched at their lower ends. As the carriage travels through a computing zone these levers 72 come one after another into engagement with the master dog 53, and when said dog is operated it 95 rocks one of the levers and lifts the Geneva wheel 71 out of engagement with the carrying wheel 40 that is then in engagement with the master wheel 38. These levers are returned to normal position by springs 75. 100 The right-hand one of the levers 72 has no Geneva wheel on it but it does have secured thereto a nose or locking tooth 76 which is adapted to lock the wheel of lowest order, which wheel I have hereinafter, for 105 convenience, called the units wheel.

All of the levers 72 extend to the upper and forward part of the totalizer where their ends normally rest against adjusting screws 77 which are secured through a supporting bar 78. Said levers are adapted to act on a universal bar 80 which is pivoted on trunnions 81 in the side plates of the totalizer. This universal bar is in the form 110 of a flanged or angled strip of metal, one flange of which overlies the ends of the levers 72 and the other of which extends downward and forward and has a concentric surface 82. The ends of the levers 72 are so shaped that when any one of them 115 is operated by the master dog, it swings the universal bar 80 upward and swings the concentric part 82 rearward over the front ends of all of the unoperated levers 72, with the result that all of said unoperated levers are 120 positively locked in their normal positions. In using the Remington-Wahl machine the operator writes the numbers in one or more columns, setting the machine for addition or subtraction, as required for each number, 125 130

and when the computation is completed he sets the machine for subtraction and writes on the paper the number indicated on the totalizer. This number being thus subtracted from itself leaves the totalizer clear; that is to say, leaves all of the wheels standing at zero; provided the total has been correctly copied. If the total has been incorrectly copied some one or more of the wheels 10 will indicate some other number than zero. In this event not only will the wrong total have been written at the foot of that particular column, but the number standing in the machine will be added into the next 15 computation and will cause an erroneous total to be written at the foot of that column of figures, even if that total is correctly copied. It is therefore highly important both that the total on the wheels be correctly copied and that at the beginning of any computation the totalizer shall be clear. I provide means for locking up the machine and thus effectually notifying the operator of the error in both cases, that is to say, 20 if the totalizer is not clear when the computation is begun and if it is not clear after the total has been copied.

My clearance-proof mechanism includes a device controlled by the state of the register as to clear or not clear. Each of the 30 pinions 68 has one tooth 83 shorter than the rest, and when the wheel indicates zero this short tooth 83 stands in the position shown in Figs. 1 and 2. In the present instance the register-state-controlled device is a feeler comb 84 consisting of a series of arms projecting from a transverse body part or rock shaft which at its ends is pivoted on trunnions 85 projecting into 35 holes in the side plates of the totalizer. This comb can swing about said trunnions and it is mounted in such position that when all of the wheels stand at zero the shortness of the teeth 83 will allow the 40 comb to drop to the forward position shown in Figs. 1 and 2, but when any pinion 68 and number wheel stands in any other position one of the longer teeth of said pinion will hold the comb in the rear position 45 shown in Fig. 3. If any one of the totalizer wheels is not at zero that will suffice to prevent the comb from dropping to its forward position. A sheet metal arm 86 is mounted 50 on the right-hand end of the feeler comb 84. As here shown an enlarged part of the trunnion 85 passes through this arm and said arm is also fastened to one of the teeth of 55 the comb by a dowel pin 87. A spring 88 connecting this arm with a stud 90 on the 60 right-hand casing plate tends to draw the arm and the comb toward the front of the machine. The arm 86 occupies the position shown in Figs. 4 and 5 and between it and the right-hand casing plate of the totalizer 18 is a latch lever 91 pivoted at its

lower end on a stud 92 projecting from the casing plate, said lever being drawn toward the rear of the machine by a spring 93 connected to a stud 94. At its upper end the lever 91 has a pin 95 projecting into a notch 96 in the arm 86, said notch being wider in a front and back direction than the diameter of the pin. The spring power tending to move the feeler comb forward, is able to overcome the tendency of spring 93 to move latch 70 lever 91 rearward. At its upper rear corner the latch lever 91 has two shoulders, namely, a lower shoulder 97 and an upper shoulder 98, said shoulders adapted to be engaged by the forward end of a lever 100 pivoted on 75 the transverse rod 74 and having a depending arm with a forward finger 101 and a rear finger 102. The lower shoulder 97 is merely a stop to limit the motion of lever 100, and said shoulder may, if preferred be 80 omitted and a fixed stop substituted. When the totalizer is in the sub-units position, that is to say, in a position one letter space to the left of that in which the master wheel 38 engages the units wheel 40, the master dog 90 85 93 lies in the notch between the fingers 101 and 102, so that if at this time a numeral key be operated and said master dog be thereby swung forward, it will rock the lever 100 as shown in Fig. 3. If at that 95 time all of the numeral wheels stand at zero, the comb 84 will be held in its forward position, shown in Figs. 1 and 2, and the lever 91 will be prevented from moving rearward under the tension of its spring 93. 100 When the key is operated therefore the lever 100 will swing up on the down stroke of the key and on the up stroke of the key will return to normal position and the whole machine will return to normal, ready for a 105 new operation. If, however, as shown in Fig. 3, one of the pinions 68 is not in its zero position, then the comb 84 will be held in its rear position, and the spring 93 will draw the latch lever 91 rearward and 110 the shoulder 98 of said latch lever will snap in under the lever 100 and hold it in its operated position. The prong 102 of said lever will prevent the master dog from returning to its normal position, and this in 115 turn will prevent the key from returning to its normal position, and the machine will be locked up, thus warning the operator that he has failed to copy the total correctly.

The devices already described can be used 120 to test the state of the totalizer before writing the first number of a calculation, but not conveniently. In order to do that it would be necessary first to move the carriage to sub-units position, then to operate the 125 clear-proof mechanism, and then to draw the carriage back to the right to begin the writing and registering of the number. I have therefore provided at the left-hand side of the totalizer additional mechanism which 130

can be operated before writing the first number and without the necessity of pulling the carriage back as just described. The left-hand end of the comb 84 has an arm 103 mounted thereon in the same manner as the arm 86 including the dowel pin 104. A left-hand latch lever 105 is pivoted to the left-hand casing plate at 106 and is drawn rearward by a spring 107, and is interlocked 10 with the arm 103 by means of a pin 108 all in substantially the same manner as the corresponding parts already described. The lever 91 has been broken away along irregular lines in Fig. 3 in order to show this mechanism. A lever 110, in all respects similar to the lever 100 and like it controlled by one of the springs 75, is pivoted on the rod 74 in position to co-operate with the latch lever 105. The construction is such 20 that if in that letter space position just preceding the one in which the master wheel engages the totalizer wheel of highest order any key be struck that controls the universal bar of the calculator, this lever 110 will be rocked by the master dog 53. If the totalizer is clear at the time the arm will return to normal position and the operator can go on with the computation, but if the totalizer is not clear then the lever 110 will be latched 25 in its operated position and the machine will be locked up and the operator thereby notified or warned that the totalizer is not clear.

Once the mechanism has warned the operator that the totalizer is not clear it has 30 performed its function and I have provided means whereby the operator can unlock the machine in order to proceed to make the necessary corrections. Such means can be variously constructed. As here shown, I have 35 mounted on the two ends of the shaft 67 on which the gears 66 are journaled, two arms 111, one of them lying just inside the latch lever 91, and the other just inside the latch arm 105, as shown in Fig. 6. Each of the 40 arms 111 has a pin 112 projecting therefrom into position to engage the inclined rear edge of the latch lever 91 or 105. One of the arms 111 is prolonged toward the front of the machine and passes through a vertical 45 slot in the front casing plate and is formed 50 slot in the front casing plate and is formed into a handle 113, by depressing which the two pins 112 can be swung upward and caused to force the levers 91 and 105 toward the front of the machine, thus releasing 55 whichever one of the levers 100 and 110 has been caught up on one of said latch levers and allowing the mechanism to return to normal position and to unlock the machine. This forward motion of these arms is permitted 60 by the lost motion of the pins 95 and 108 in the notches 96 in the arms 86 and 103.

I have provided means to hold the feeler comb 84 out of contact with the pinions 68 during the time when said pinions are being turned by the numeral keys. This is

a decided advantage in apparatus of this sort, as it prevents the rubbing of the ends of said teeth over said comb. On one end of the universal bar 80 I have mounted an arm 114, relative turning motion between 70 which and the universal bar is prevented by a dowel pin 115, this arm being shown in the present instance on the right-hand end of the universal bar. The arm 86 has a finger 116 projecting into the path of the 75 arm 114 in such wise that whenever the universal bar 80 is operated by the lifting of one of the levers 72, the arm 114, acting on said finger, swings the arm 86 and the feeler comb 84 rearward out of contact with the pinions 68, and so maintains them during the entire down stroke of the key, and therefore during the entire time when any pinion is turning.

The testing of the state or condition of 85 the totalizer can be done by any key that operates the universal bar of the calculating mechanism. A special key can be connected up for the purpose, if desired, but I prefer to use the ordinary zero key of the machine, 90 which operates the universal bar but does not operate the differential shaft 32.

Various means can be provided to assure that the operator works this key before beginning a computation and also immediately 95 after writing a total. The means here adopted consists in placing on the type bar 11, Fig. 7, that is connected with said zero key, an upper case character 117 which is here shown as a star. This star can be 100 printed by first depressing the case shift key 12 and then operating the zero key 10. It is contemplated that a rule of operation be enforced according to which the operator must write this star before the first item of 105 every computation and immediately after every written total. The presence of this star on the paper in the two positions indicated, shows that the operator applied the test and that if there was any error he was 110 apprised of that fact and presumably corrected it.

Various changes can be made in the details of construction and arrangement without departing from my invention.

What I claim as new and desire to secure by Letters Patent, is,

1. In a calculating machine, the combination of a totalizer and an actuator, one traveling relatively to the other, a set of 120 keys, a register-state-controlled device in said totalizer, and two key operated devices one at each side of the totalizer whose action is controlled by said register-state-controlled device to indicate to the operator the state of 125 the register as to clear or not clear.

2. In a calculating machine, the combination of a totalizer and an actuator, one traveling relatively to the other, a set of keys, a register-state-controlled device in said total- 130

- izer, two latches one at each side of said totalizer and both controlled by said register-state-controlled device, and two key operated levers one controlled by each of said latches so as to indicate to the operator the state of the totalizer as to clear or not clear. 3. In a calculating machine, the combination of a totalizer and an actuator, one traveling relatively to the other, a set of 10 keys, a register-state-controlled device in said totalizer, two key operated devices one at each side of said totalizer, a lock to lock up the machine, and means whereby said lock is controlled by each of said key operated devices under the control of said register-state-controlled device. 4. In a calculating machine, the combination of a totalizer and an actuator, one traveling relatively to the other, a set of 20 keys, a register-state-controlled device in said totalizer, two key controlled devices one at each side of said totalizer, and means controlled by said register-state-controlled device for preventing a complete operation of 25 said key controlled devices and of the key which operates them in case the register is not clear. 5. In a calculating machine, the combination of a totalizer and an actuator one traveling relatively to the other, keys, a register-state-controlled device in said totalizer, two key operated levers one at each side of said totalizer, latches for said levers controlled by said register-state-controlled device, and a releasing device for said latches comprising a rock shaft extending across the totalizer and having arms one acting on each of said latches. 6. In a calculating machine, the combination of a totalizer and an actuator, one traveling relatively to the other, said totalizer containing a series of register wheels, and a register-state-controlled device, a set of keys for operating said register wheels in one denomination after another, means whereby any key when operating on any register wheel moves said device out of engagement with said register wheels, and means whereby one of said keys when operated in sub-units position has its operation controlled by said device so as to indicate to the operator whether or not the totalizer is clear.

Signed at the borough of Manhattan, city of New York, in the county of New York and State of New York this 5th day of July 1921.

ARTHUR F. POOLE.
